CONTINUOUS FEEDER

Frank J. Breman, Chicago, Ill.

Application January 25, 1950, Serial No. 140,480

24 Claims. (Cl. 271—37)

1

My invention is primarily concerned with a new and improved mechanical feeding mechanism for continuously supplying the printing cylinders or printing couple of a printing press, or the like, with sheets of paper.

More precisely, my invention is directed to a simple mechanical feeder adapted to supply paper sheets to the main feeder rolls for example, of an offset printing press, to eliminate the hand feeding of individual sheets.

In printing newspapers, forms or the like with an offset printing press, it is essential for a smooth and efficient printing cycle, that the sheets to be imprinted be constantly supplied to the feeding rolls of the press. The time interval available for this supply operation may be measured by the time consumed for the printing plate to transfer its image to the blanket cylinder. As the platen cylinder approaches the blanket cylinder, the sheet of paper must then be fed onto the platen to be gripped by suitable fingers mounted thereon so that as the platen cylinder rotates with the blanket cylinder, the image impressed thereon may be properly transferred to the paper. Several problems present themselves in attempting to supply mechanically the feeding rolls with paper sheets, chief of which are the following:

(1) The assurance that a single sheet of paper will be supplied to the feed rollers of the press at one time;

(2) The proper alignment of the paper as it is introduced to the feed rollers, to ensure accurate alignment and registry of the image during transfer thereof from the blanket cylinder to the paper sheet; this is especially important when more than one color of printing medium is involved; and

(3) The proper synchronization of the supply feeding operation with the feed rollers, plate, platen and blanket cylinders of the press to ensure a steady uninterrupted printing operation.

I have solved the operational problems of such a mechanical continuous supply feeding system and in certain preferred embodiments of my invention herein disclosed have applied my invention to a simple compact feeding mechanism adapted to be adjoined to offset printing presses presently available on the market. Briefly, my feeding device constitutes a roller synchronously driven with the rotative plate and platen cylinders and adapted to feed a single sheet of paper to the feed rollers of the press at one time, simultaneously ensuring a positive alignment of the

2

paper before introduction thereof to the feed rollers.

It is the primary object of my invention to provide a new and useful simple mechanical continuous feeder for supplying sheets to the printing cylinders or printing couples of printing presses or the like.

It is an important object of my invention to disclose a new gravity and mechanical type feeding device adapted to feed positively a single sheet of paper to printing presses or other devices to which it is desired to feed sheets.

It is another object of my invention to disclose a new and useful continuous feeder for use with printing presses which will guarantee proper alignment of the sheets in the feeding rollers of the press.

It is a further object of my invention to provide a continuous mechanical feeder for use with printing presses or the like, capable of adjustable refinement to adapt its use to paper of differing weights, thicknesses and widths.

It is a still further object of my invention to display a new mechanical and gravity style continuous supply feeder adapted to supply synchronously sheets of paper to an offset printing press or the like in accordance with the printing cycle of the press to thereby ensure a smooth and continuous automatic printing and feeding operation.

These and other objects will appear from time to time as the following specification and description proceeds.

For the purpose of illustrating to those familiar with the printing and sheet feeding art, the mode of utilizing and constructing my invention, reference is herein made to a typical type of printing press to which my device is readily adaptable, as illustrated in the pending application of William Ward Davidson, entitled Printing Press, Serial No. 68,458, filed December 31, 1948, now Patent No. 2,561,015, dated July 17, 1951, which in conjunction with the following descriptive matter will make my invention readily more understandable, reference being made as well to the accompanying drawings, in which:

Figure 1 is a partial side elevational view of my feeder made in accordance with the principles of my invention, shown in its mounted position on an offset type of printing press as illustrated in the Davidson application, Serial No. 68,458 of reference herein;

Figure 2 is a partial top plan view of the machine and feeder shown in Figure 1 at an enlarged scale thereover;

Figure 3 is a detailed partial side elevational view showing the particulars of the several linkage arrangements used in my continuous feeder;

Figure 4 is an enlarged detailed side elevational view with parts broken away in section, taken substantially along the line 4—4 of Figure 2;

Figure 5 is an enlarged partial detailed side elevational view of the jogger mechanism of my feeder, taken substantially along line 5—5 of Figure 2;

Figure 6 is an enlarged transverse sectional view of the jogger mechanism, taken along line 6—6 of Figure 5;

Figure 7 is a detailed left side elevational view of an alternate feeder linkage shown with the left end cover plate removed, displaying the linkage positions when the feed roll is in position to feed paper to the press;

Figure 8 is a partial side elevation showing the position of the stop fingers when the feed roll is down as shown in Figure 7;

Figure 9 is another side elevational view of the alternate feeder linkage shown in Figure 7, showing the linkage positions when the feeder is not feeding paper sheets to the press;

Figure 10 is a view similar to Figure 8 showing the stop fingers in an up position when the feed roll is in its non-feeding position shown in Figure 9;

Figure 11 is a plan view showing the clutch arrangement used in the alternate feeder shown in Figure 7; and

Figure 12 is an enlarged detailed side elevational view showing the retard roll adjustment control positioned at the right hand side of the alternate feeder.

Referring now to Figures 1 and 2 of the drawings, an offset press indicated generally at 20, being the type described in the referred to Davidson application, Serial No. 68,458, as an illustrative example of a typical style of press with which my invention may be utilized, comprises an exterior shell 21 in which is housed a large centrally disposed cylinder 22, the cylindrical surface of which is provided with a plate segment 23 and a platen segment 24. The cylinder 22 is driven by suitable gearing 25 and located above the cylinder 22 is a smaller blanket cylinder 26 having a diameter equal to the radius of the cylinder 22. A set of feed rollers and accompanying mechanism indicated at 27 is adapted to feed sheets of paper between the rotating central and blanket cylinders. Wetting rolls 28 and inking rolls 29 are located for intermittent tangential contact with the plate 23 mounted on the cylinder 22 to thereby coat it with the proper registering medium, all of which is described more fully in the Davidson application of reference, Serial No. 68,458, and will not be set forth in further detail herein.

Coming now to the primary features of my invention, comprising an automatic continuous feeder, indicated generally at 31, and including a feeding tray 32, a rotatable feed roll 33, a stationary retard roll 34, a set of stop fingers 35 and a jogger mechanism 36. For clarity of description, each of the above elements will be described in conjunction with its associated functioning apparatus as follows:

The tray 32 is comprised substantially of an inclined bottom plate 40 on which are mounted a pair of angular side plate members 41, adapted to be positioned laterally across the bottom plate for adjusting the tray to paper sheets of varying widths. The side plate members 41 are formed

of sheet metal having a rectangularly formed bend running along the length thereof to form vertically extending sides for guiding paper or the like during gravitationally imposed downward

sliding movement across the tray bottom, as will appear more clearly hereinafter. Supporting ribs 42 are disposed beneath the tray bottom 40 to add rigidity to the tray member 32. A finger opening 43 may be disposed centrally of the tray bottom 40 to provide accessible means for grasping the stack of paper on the tray for removal or loading thereof. End plates 44 and 45 are connected at the inner end of the tray 32 to the supporting ribs 42 and may be cross-connected by a rigid angle iron threshold bar 46 disposed inwardly of the lower end of the tray 32 toward the press for providing rigidity to the tray construction. The end plate 44 disposed at the left-hand side of the machine, looking from the tray towards the blanket cylinder 26, is connected to an angular frame member 47 secured to a vertically disposed hinge block 48 by means of cap screws 49 inserted through an elbow plate 50. The hinge block is suitably pinned for swinging pivotal movement between a pair of pivot blocks 51 secured to the left-hand side wall 52 of the press shell 21, as will be clearly seen in Figures 2 and 3.

Looking at the upper portion of Figure 2, the right-hand end plate 45 of the feeder is secured to the right-hand side of the press shell 21 by means of a latch bar 53 adapted to slide over a latch pin 54 mounted in the right-hand side wall 55 of the press shell 21. By the means of such a latching and hinging arrangement, the tray is adapted to swing laterally about the hinge 48 providing ready, inspection accessibility to the feed rollers 27 of the printing press 20, and also permitting ready accessibility to the various linkage mechanisms associated with the feed roll 33 of the feeder 31.

The feed roll 33 comprises a short metal cylinder having a rubber facing and mounted on a shaft 56 extending laterally between a pair of bell cranks 57 and 58, the shaft 56 being mounted thereon for rotational movement in suitable bearings 59. The bell cranks 57 and 58 are suitably pivoted to the end plates 44 and 45 for rocking movement on pivot pins 60. A cylindrical tie rod 61 is also connected between the two bell cranks 57 and 58 to provide rigidity to the construction and connective means for simultaneously actuating the two bell cranks, as will appear presently herein.

The shaft 56 extends through the bell crank 57 at the left-hand side of the machine, that is the side shown near the lower edge of Figure 2, to be received by a cam opening 64 formed in a sliding cam plate 65, slidably connected to the left-hand end plate 44 by means of a projecting pin 66 mounted on the end plate 44 and insertable in suitable longitudinal slotted apertures 67 formed in the cam plate 65. The cam plate is adapted to raise and lower the feed roll 33 and shaft 56 through means of the cam opening 64 formed at its inner end during lateral reciprocating motion, as will appear more clearly in the use and operational description hereinafter.

A pinion gear 68 is mounted at the left-hand end of shaft 56 and is interconnected with a suitable ratchet type override clutch 69 for allowing positive movement of the shaft and pinion in one direction only. A rack member 70 is disposed in vertical tooth contacting rela-

tion with the pinion for rotatably actuating the shaft and feed roll during the feeding operation of the feeder mechanism. A suitable guide sleeve 71 may be provided in surrounding relation with the rack for providing guiding means for the rack during its vertical racking movement, the guide being mountable around the feed roll shaft 56 at the left-hand end thereof adjacent the pinion 68.

A crank arm 74 formed in the shape of a letter J is connected to the lower end of the rack for vertical actuation thereof, driving connection being had with a stem portion 75 of a T-shaped double bell crank member 76 pivotally mounted by a centrally disposed pin 77 to a projecting lug portion 78 integrally associated with the left-hand end plate 44. The double bell crank 76 is actuated with intermittent rocking motion about the pin member 77 by means of a connecting rod 79 having adjustable turn buckle end connectors 80 disposed between the lower arm of the double bell crank 76 and a crank plate 81 connected to a central shaft 82 supporting the cylinder 22 of the press, as is clearly seen in Figure 1 of the drawings. The connecting rod is detachably connected to the bell crank 76 to allow the feeder to be swung laterally about the hinge 48. A spring 83 is disposed about the pivot pin 77 between the double bell crank and the lug 78 connected to the end plate, which spring is adapted to be biased by the rocking motion set up by the connecting rod and rotating crank plate associated with the shaft 82 of the central cylinder 22 to provide returning pressure on the double bell crank 76 during operation of the mechanism. A suitable connecting pin 85 may connect the J lever link with the stem of the T-shaped double bell crank as is seen in Figure 3; being connected therewith through an adjusting slot 86 for regulating the throw of the J lever and rack.

An upper arm 87 of the T-shaped bell crank member 76 is provided with a protruding lug 88 connected rigidly to a rod 89 having adjusting nuts 90 on its opposite end for varying its length. The rod 89 is slidably inserted through a block member 91 rigidly fastened to the sliding cam plate 65. During counterclockwise rotation of the double bell crank, as viewed in Figure 3, the rod 89 slides through the block to provide a lost motion connection, the block 91 being eventually engaged by the nut 90 on rod 89 adjacent the lug 88 to cause positive sliding movement of the cam plate 65 to the left which results in the feed roll 33 being lowered by the cam opening 64 for proximate contact with the retard roll 34. Conversely, clockwise movement of the double bell crank allows the adjusting nuts 90 on rods 89 to engage the block 91 associated with cam plate 65 resulting in reciprocal returning motion of the cam plate to the right culminating in raising the feed roll 33 away from the retard roll 34.

The retard roll 34 is mounted centrally below the feed roll 33 and is rigidly held in a holding bracket 94 by means of a shaft bolt 95; the holding bracket being rigidly secured to a rectangular cross bar 96 pivotally mounted at its ends between the end plates 44 and 45. The retard roll does not rotate about the shaft bolt but is rigidly held therewith by the bracket 94 to provide a wiping action to the underside of a sheet of paper being fed thereacross. Adjustable movement of the retard roll 34 is accomplished by means of an adjusting elevating

screw 97, mounted to the right-hand end plate 45 by means of a depending ear member 98 projecting therefrom near the upper edge of the end plate 45. Looking at Figure 4, it will be seen that the elevating screw 97 is provided with a knurled knob 99 at its upper end and is connected to a crank 100 at its lower end. The crank is pivotally connected between the lower end of the elevating screw and the rectangular cross bar 96 so that upon turning the knob 99 in a clockwise direction, as viewed from the top, a threaded portion of the screw, not shown, engages with a threaded interior of an opening in the depending ear 98 extending from the end plate to elevate the screw, thereby pulling the crank 100 upwardly which causes counterclockwise rotation of the bar 96 as seen in Figure 4, resulting in an elevating movement of the bracket 94 holding the retard roll 34. Conversely, counterclockwise motion of the knob causes a lowering of the retard roll. This vertical adjusting movement of the retard roll acts to adjust the contact pressure between the retard and feed rolls during the feeding operation of a sheet of paper; the adjusted contact pressure serving to ensure the feeding of a single sheet of paper between the rotatable feed roll and the stationary retard roll.

The stop fingers 35, as seen in Figures 2 and 3, are provided for holding the pile of paper on the tray 32 during periods when the feed roll is out of contact with the retard roll and no paper is being fed between the two rolls. The two stop fingers 35 are mounted on a cylindrical shaft 102 provided with a central U-shaped bend 103 adapted to clear the retard roll mounting. The ends of the shaft 102 are rotatably mounted in the end plates 44 and 45 the right-hand end being provided with a coil spring 104 connected to the shaft 102 and the end plate 45, and adapted to be biased with torsional load during the clockwise rotation of the shaft when the fingers are raised to their stopping position, as shown in Figures 3 and 4. Means for actuating the stop fingers in their raised and lowered position is provided at the left-hand side of the machine comprising a latch bar 105 mounted at the outer left-hand end of shaft 102 adapted to be held in the position shown in Figure 3 in which spring 104 on the right-hand end of the shaft 102 is in biased torsional loaded position, by means of a bell crank 106 having a detent 107 on its lower arm 108 and a retrieving spring 109 at its upper arm 110. The bell crank is pivotally interconnected with the end plate 44 by means of pivot pin 111. Counterclockwise movement of the bell crank 106 causes tensional loading of retrieving spring 109 which is positioned in such a manner as to constantly urge the bell crank 106 to the right in a clockwise movement as seen in Figure 3. Counterclockwise movement of the bell crank 106 is caused by means of a depending rod 112 projecting downwardly from a cocking bar 113 pivotally connected at its outer end to the upper arm of the double bell crank 76 and having a cocking detent 114 at its inner end adapted to engage a male lug 115 at the upper end of the latch bar 105.

The cocking bar 113 is urged in a downwardly counterclockwise direction by means of a coil spring 116 interconnected with the cocking bar and the double bell crank 76, clockwise movement of the double bell crank causes the cocking bar 113 to move to the right as seen in Figure 3, causing its cocking detent 114 to engage the

projecting lug 115 of the latch bar to force it in a clockwise direction until it reaches the position shown in Figure 3 where the detent 107 on the bell crank 106 under urging pressure of the retrieving spring 109 engages the lower end of the latch bar to hold it in that position. Such a clockwise movement of the latch bar causes the attached shaft 102 to move in a clockwise direction thereby raising the fingers to the position shown in Figures 3 and 4. Conversely, counterclockwise movement of the double bell crank 76 causes the cocking bar to move to the left bringing the rod 112 into contact with the upper arm 110 of the bell crank 106 thereby causing counterclockwise movement of that bell crank to release the latch bar 105 from detent 107 allowing the spring 104 at the right-hand end of shaft 102 to move the shaft in a counterclockwise direction to lower the stop fingers 35 to a non-interfering position with the paper being fed between the feed and retard rolls. Lateral adjustment of the position of the stop fingers on shaft 102 is accomplished by means of adjusting screws 117 adapted to contact the lower side of shaft 102 and in connective association with the stop fingers as is seen in Figure 4.

As the stop fingers 35 are raised, as described above, a side jogger is actuated to come in contact with the one side of the stack of paper positioned on the tray 32. The jogger 36 serves to keep the stack of paper properly positioned on the tray and holds the stack in proper feeding condition wherein the sheet ends are fanned or cascaded at a forward upper slope adjacent the retard roll so that there is proper alignment and registration of the sheets of paper as they are fed between the feed and retard rolls. Actuation of the jogger is accomplished by means of a crank bar 119 connected to the shaft 102 carrying the fingers 35 with a cam link 120 having an offset bend therein pinned thereto for pivotal movement by means of a pin 121. The cam link 120 is provided with a slotted aperture 122 at one end for providing lost motion to the jogger linkage; the length of the aperture 122 being designed to properly time the actuation of the jogger in relation to the feed roll and the holding fingers. A rod 123 is journaled in the slotted aperture 122 and is provided with a coil spring 124, as seen in Figure 6, having abutting engagement with a pin 125 and a back plate 126 of the jogger. A face plate 127 is provided with a felt or sponge rubber covering adapted to frictionally engage the edges of the sheet of paper or the like to complete the mechanical make-up of the jogger mechanism. In operation, the cam link 120, having a bent profile section therein, is pushed along the pin 123 to engage the face plate of the jogger upon rotation of shaft 102 through the crank bar 119 thrusting the face plate away from the back plate 126 thereby pulling rod 123 therewith which compresses spring 124. On further rotation of the shaft 102 the link 120 of the jogger is pulled backwardly to release the compressive force on the spring 124 whereby the jogger plate will return to its initial position.

The operation of the above described machine is probably apparent from the foregoing description, but for the sake of clarity, I shall briefly describe the operational cycle of the feeder to show the sequential relation of the several linkages involved.

The feeder is shown in Figures 1 and 3 at the completion of a feeding stroke with the feed roll

in its upper position away from the retard roll 34, and the rack 70 near its upper limit of travel with the stop fingers positioned vertically to hold the stack of paper on tray 32 during the printing cycle, when the platen cylinder contacts the blanket and a paper sheet is being fed to the platen by the feed rollers 27 of the press.

It will be seen that the shaft 82 and attached crank plate 81 rotate counterclockwise causing the double bell crank 76 to rotate in the same sense for the next 90° or so of the crank plate's rotation. Rocking of the double bell crank from its position shown in Figure 1, in a counterclockwise direction, creates the following sequence of movements: The stem 75 of the bell crank 76 moves downwardly, causing the J link 74 to pull the rack 70 in a downward direction. The feed roll does not rotate during the downward travel of the rack, due to the override clutch 69 which permits positive rotation of the shaft 56 in a clockwise direction only, as viewed in Figure 1. As the rack 70 nears its downward limit of travel, the rod 112 attached to the cocking bar 113 contacts the upper arm 110 of the bell crank 106, pulling therewith its detent 107 out of engagement with the lower end of the latch bar 105, allowing the torsionally loaded spring 104 located at the opposite end of shaft 102 and associated with the stop fingers 35 to urge the stop fingers downwardly in a counterclockwise sense to a non-interfering position. Concurrently, with the finger's actuation, the crank 119 associated with the jogger 36 is moved with shaft 102 to pull the cam linkage 120 downwardly to disengage the jogger from the stack of paper on tray 32. It should be noted in this connection, that the jogger linkage has enough lost motion to allow its disengagement from the paper stack only after the fingers are completely down, and the feed roll has been lowered in feeding proximity with the retard roll so that at all times the stack of paper is held by some means from freely slipping into the feed roll members 27 of the press.

Meanwhile, the rod 89 connected to the protruding lug 88 on the upper arm 87 of the double bell crank 76 has been sliding through the block member 91 connected to the cam plate 65. Further movement of the double bell crank to the left as viewed in Figures 1 and 3, causes the lug 88 to contact block 91 to urge the cam plate 65 to the left, causing the cam opening 64 to be moved to the left resulting in the feed roll 33 and shaft 56 being lowered to a feeding position with the feed roll in proximate contact with the surface of the retard roll 34. The above operations consume approximately the time required for the crank plate to turn 90°, or to the point where the connecting rod is at its limit of travel to the right, as viewed in Figure 1.

Conversely, movement of the double bell crank in the opposite direction, or to the right, as viewed in Figures 1 and 3, causes the rack which is now in its downward position, as described above, to move upwardly to rotate the feed roll by means of the uni-directional clutch and pinion, to feed a sheet of paper to the feed rollers 27 of the press, which will be in non-feeding position during the feeding operation by my feeder attachment. In this connection, it may be appropriate to observe that the feed roll 33 remains in feeding contact with the sheet of paper for about 50% of the sheet's length, driving the sheet against stops associated with the feed rollers 27 of the press, and is then raised by virtue of the rod 89 engaging the block 91 on the cam plate to pull that

plate back to the right again to its Figure 3 position. Simultaneously, with the raising of the feed roll the stop fingers are raised and the jogger thrown "in," thereby allowing the single sheet of paper, now against the stops of the press feeding couples, to lie freely over the top of the raised stop fingers except for aligning engagement by the side jogger. The sheet is then fed to the printing couple of the press by feed rollers 27; the jogger simultaneously aligning the single sheet of paper and holding the stack on tray 32.

As the double bell crank moves back pushing the rack upwardly, the cocking detent 114 of the cocking bar 113 engages the male lug 115 on the upper end of the latch bar 105, thus raising the stop fingers 35. Simultaneously, with this actuation of the stop fingers, the depending rod 112 on the cocking bar, tending to press the bell crank 106 downwardly and load the retrieving spring 109 associated therewith, is moved with the cocking bar to the right, allowing the bell crank 106 to rotate clockwise to engage the lower end of the latch bar, so that its detent 107 may hold the latch bar and connected stop fingers in an upright position as seen in Figure 3.

Thus, it is seen that a perfect operating cycle is provided, my feeder mechanism having the ability to feed the paper sheets to the press in proper timing sequence with its operation, and providing means for centrally and constantly holding and lining up the stack of unprinted sheets on the tray 32 so that they will not fall freely into the press. Briefly, in this respect, it is worth mentioning that during the non-feeding stage when the feed roll is up, the fingers are up to hold the stack of paper from sliding into the press, and the jogger is "in," engaging the stack along one edge to hold the sheets in their desired cascaded or fanned end relation with one another which might otherwise be disturbed by the vibrations of the press. The jogger additionally contacts one edge of the single paper sheet previously fed to the stops of the press feeding couple 27 for proper registering alignment thereof prior to its being fed to the printing couple of the press.

Referring now to Figures 7, 8, 9 and 10 in which my alternate feeding mechanism 131 is displayed as a type adapted for mounting on an offset printing press in a manner similar to the previously described feeder 31. In functional result the two feeders are equivalent, but I have found my alternate mechanism to be more successful in practical operation and use. The actuating linkage arrangement, it will be readily perceived, differs somewhat from the linkage of feeder 31 described heretofore, but the alternate feeder 131 includes essentially equivalent elements comprising a feeding tray 132, a rotatable feed roll 133, a stationary retard roll 134, a set of stop fingers 135, and a jogger mechanism 136; the main differences between the two feeders being in the actuating linkage which is associated with each of these various elements.

The feeding tray 132 comprises a bottom plate 140, side members 141, and supporting ribs 142, all made of sheet metal and associated in substantially identical relation as previously described in connection with tray 32 associated with my first mentioned feeder 31. An additional feature is introduced in the tray 132 comprising a tilting adjustment composed of a pair of slotted arcuate openings 143 in supporting ribs 142 registering with similar openings 143' in a left-hand end plate 144, and a similar right-hand end plate

145. The openings in the two plates and ribs are adapted to receive suitable bolts 146 capable of holding the tray in various selected tilting positions, a bolt adjustable connecting each of the two ribs 142 to the right-hand end plate 145 and the left-hand end plate 144, respectively. Pivotal connection between the inner end of the tray and the feeder framing is made by a pair of tap screws 147, the inner ends of which are journaled in projecting bars 148 extending outwardly from the inner end of the tray supporting ribs and positioned adjacent the two end plates. Lateral positioning adjustment of the tray side walls 141 is accomplished by means of set screws 149 adapted to engage the underside of the tray bottom 140 and positioned at the upper end of each side wall in a non-interfering position with the paper normally stacked on the tray.

The left-hand end plate 144 is similar in most respects to the right-hand end plate 145 with the exception that whereas the right-hand end plate is a flat plate, the left-hand end plate is fitted with an extending lip 150 projecting outwardly from its inner edge at right angles thereto. The lip is adapted to be fastened to a pair of angularly bent ear members 151 protruding inwardly in their mounted position from the upper and lower reaches of the lip 150. The ears are provided for mounting connection of the tray to a hinge pin 152 extending through the two ears and rigidly positioned vertically between a pair of hinge blocks 153 securely fastened to the left-hand side wall 52 of the shell 21 of the press.

The right-hand end plate 145 is fitted with a latch bar 154 pivotally mounted thereto by a pivot pin 155 and adapted to receive a latch pin 156 mounted to and protruding from the right-hand side wall 55 of the shell 21, similar to the latching arrangement described heretofore in connection with the first mentioned feeder 31. This combined latch and hinge arrangement allows the tray and accompanying feeder mechanism to swing laterally about the hinge pin 152 to give access to the various linkages if need be without disconnecting the driving connection leading from the press, as is necessary with my first described feeder 31. A rectangular cross sectional bar 151 is positioned near the lower inner edge of the two end plates extending therebetween to rigidly tie the two plates together to thereby provide a sturdy feeder frame construction.

The feed roll 133 is similar in all respects to the feed roll 33 described previously in connection with my feeder 31 and is cylindrical in form with a rubber coated surface adapted to frictionally engage the upper surface of a sheet of paper for feeding thereof to the feeding rolls 27 of the press 20. Feed roll 133 is mounted intermediately of the two end plates on a cylindrical shaft 158 for rotational movement therewith.

The shaft 158 is rotatably mounted between a pair of bell cranks 159 and 160, pivotally mounted to the left and right hand end plates 144 and 145, respectively, by pivot members 161. A cylindrical cross connecting rod 162 is also mounted between the upper arms of the two bell cranks for rigidly tying them together to ensure their simultaneous actuation, as will more clearly appear presently.

It will be noted, on inspection of Figures 7 and 9, that the bell crank 159 disposed at the left side of the feeder is provided with an extended portion having a roller type cam follower 163 attached thereto adapted to follow a curved camming surface of a cam aperture 164 formed in the

upper end of a rocker arm 165; movement of the cam follower along the camming aperture causes rocking motion of the bell cranks 159 and 160 about pins 161 to raise and lower the shaft 158 and attached feed roll. A spring, not shown, may be connected between the bell crank 159 and the left-hand end plate to maintain the cam follower 163 in constant contact with the cam surface of the camming aperture 164.

The rocker arm 165 is actuated by a to and fro movement of a kick plate 168 provided with adjustable hammer members 169 for contacting an anvil block 170 rigidly secured to, and projecting from, the back face of the rocker arm as seen in Figures 7 and 9. The rocker arm and kick plate moves relative to one another in arcuate paths about a common shaft 171 extending transversely across the feeder between the two end plates; the kick plate 168 and rocker arm 165 being separated by a spacer sleeve 172. The kick plate is actuated by an offset intermediate drive lever 173 in the form of a bell crank; connection therewith being through an oppositely offset intermediate link 174 pivotally secured to both the kick plate and the intermediate drive lever 173 by pivot pins 175.

The intermediate drive lever 173 is rotatably mounted behind the left-hand end plate as seen in Figures 7 and 9 on a solid shaft 176 adapted to be received within an internal cylindrical opening of an intermediate drive lever pivotal bearing 177 rigidly secured to the left-hand end plate and extending therethrough to project outwardly from the outer surface thereof.

A clutch engagement lever 180 in the form of a bell crank is provided with a projecting clutch engaging block 181 located near its outer end, which block is adapted to receive a projecting external cylindrical portion of the intermediate drive lever pivot bearing 177 to thereby provide pivotal mounting for the clutch engagement lever on the left-hand end plate.

A pin type clutching arrangement, shown clearly in Figure 11, is provided for selective operative connection between the clutch engagement lever 180 and the intermediate drive lever 173. This clutch arrangement comprises chiefly, a cylindrical rod 182 extending laterally between and through the two end plates 144 and 145. The right-hand end of the rod 182 outside the right-hand end plate 145 is provided with a vertical handle member 183 adapted to be engaged by "in" and "out" steps 184 and 185 respectively, in a block member 186 secured to the outside of the right-hand end plate. A compression spring 187 surrounds the rod 182 inside the right-hand end plate, and between the plate and a holding collar 188 surrounding the rod and rigidly secured thereto. At the left-hand end of the clutching arrangement, the rod 182 is fitted with a bifurcated fork member 189 projecting at right angles therefrom and adapted to receive the head of a clutch pin 190 for sliding arcuate movement therealong. The clutch pin 190 extends through an upper arm 191 of the intermediate drive lever, through a suitable arcuate slotted aperture, not shown, in the left-hand end plate and into a receiving hole 192 in the engaging block 181 mounted to the back side of the clutch engagement lever 180, to complete driving connection between that lever and the intermediate drive lever 173 and make a rigid link out of these two levers when the clutch pin is "in."

The clutch engagement lever 180 is rocked with an arcuate motion about the intermediate

drive lever pivot bearing 177 by a driving shuttle spool 195 mounted for sliding vertical and rotatable movement on the hinge pin 152. A fork 196 is pivotally connected to the offset inner arm 5 of the clutch engagement lever 180 and projects at right angles from the inner face thereof to engage a suitable annular channelled groove 197 extending around the upper end of the spool 195 thus providing driving connection between the spool and the clutch engagement lever.

The spool 195 is reciprocally driven along the hinge pin by an offset feeder drive bell crank 198 pivotally mounted to, and outside of, the left-hand side wall 52 of the press shell 21; an upper arm 199 of the bell crank 198 being fitted with a fork 200 similar to fork 196 adapted to meet with another annular channelled groove 201 surrounding the lower end of the spool 195 to provide driving connection therebetween. A lower depending arm 202, inset from the upper arm 199, is pivotally joined at its inner end to a straight connecting rod 203 pivotally connected to a crank plate 204 mounted on the extended end of the main central shaft 82 of the press to complete the driving connection to the feeder linkage. Connection of the connecting rod 204 with the crank plate is made in an off-center pivotal position to thereby provide proper cranking motion.

Rotational movement of the feed roll 133 is furnished by means of a rack 208 connected at its lower end in a pivot block 209 which is pivotally connected to an inwardly extending arm 210 of the kick plate 168. A slotted opening 211 is provided in the adjacent kick plate arm for connecting the pivot block 209 and attached rack in various adjusted positions relative thereto for regulating the vertical throw of the rack.

A one way override clutch 212 is mounted on the shaft 158 inside the bell crank 159 adjacent a pinion 213 which engages the rack in a manner similar to that described previously in connection with the first mentioned feeder 31. This override clutch allows rotation of the feed roll 133 and the shaft 158 in a clockwise direction only to ensure feeding of the paper sheets to the press. It will be seen that vertical arcuate movement of the kick plate arm 210 causes a responsive vertical movement of the rack 208 to rotate the shaft 158 during the downward stroke of the rack through the pinion 213, while the clutch 212 allows the rack and pinion to override during the upward stroke of the rack and the kick plate arm.

The retard roll 134 is in all respects the same as the retard roll 34 of my previously described feeder, being essentially a non-revolving roller rigidly mounted in a holding bracket 215 fastened to a pivotal cross bar 216 positioned between the right-hand end plate and a vertically positioned intermediate frame member 217 for pivotal movement.

Adjustment of the retard roll 134 toward or away from the feed roll 133 is accomplished by an elevating screw 218 mounted to the right-hand end plate, having a knurled knob 219 at its upper end and connecting with the pivotal cross bar 216 by a crank 220 the same as previously described in connection with my first mentioned feeder 31. A tensioning spring 221 is provided below mounting bracket 222 mounted to the right-hand end plate 145 for tensioning the adjustment movement of the threaded elevating screw 218. Briefly, the threading adjustment of the elevating screw up or down causes the cross bar to rotate, to raise or lower the feed roll toward or away from the retard roll.

The stop fingers 135 comprise essentially a pair of projecting rectangular metal fingers mounted on a square cross section finger bar 225 extending between the right-hand end plate 145 and the vertically positioned frame member 217 which is rigidly fastened to the rectangular cross bar 155. It should be noted that the fingers may be adjustably positioned on either side of the stationary retard roll by merely sliding them along the finger bar 225; a leaf spring, not shown, positioned between each finger and the finger bar serving to exert frictional pressure on brackets 226 holding the stop fingers on bar 225 to maintain the selective positioning thereof. The finger bar 225 is cylindrical in cross section at each end and is rotatably mounted through the right-hand end plate and the intermediate vertically positioned frame member 217. A torsional spring, not shown, but similar to spring 104 previously described in connection with feeder 31, is employed at the end of the rod 225 adjacent the right-hand end plate 145 to exert return turning force on the rod.

Rotational movement of the finger bar is accomplished by a suitable linkage arrangement at the left-hand side of the feeder comprising a small connecting link 227 rigidly mounted on the finger bar 225, and pivotally connected at its outer end to the inner end of the curved intermediate lever 228 positioned in offset relation to a vertical bell crank 229. Operative connection between the intermediate lever 228 and the lower arm of the vertical bell crank 229 is made by means of a cylindrical offset post 230 rigidly fastened to the lower arm of the bell crank 229 and about which the outer end of the intermediate lever is free to pivot. The vertical bell crank 229 is pivotally mounted on a pivot post 231 projecting from the inner face of the left-hand end plate, shown cut away at this connection in Figures 7 and 9. The upper arm of the vertical bell crank 229 is provided with a rotatably mounted roller 232 projecting outwardly therefrom to contact and roll along an upper camming edge 233 of the rocker arm; this camming edge causing the vertical bell crank 229 to rock about the pivot post 232 to give up and down actuation to the stop fingers through the intervening linkage just described. A spring 234 is connected between the vertical bell crank, below its pivot point, and a post 235 projecting from the inner surface of the left-hand end plate to maintain the roller 232 in contact with the camming edge 233 of the rocker arm.

The jogger mechanism 136 may best be understood by reference to Figures 11 and 12 wherein it will be seen that an end frame member 236 extends vertically from the tray bottom 140 and is adjacent to, and extending from, a back wall frame member 237 projecting vertically from the tray bottom 140. The back wall 237 and end frame 236 are rigidly bolted to the side plate 141 of the tray 132 by bolt 238. A vertically positioned jogger plate 239 faced with sponge rubber or other suitable material extends vertically, substantially in line with the vertical side plate 141 of the tray at the lower end thereof, and communicates with a cylindrical boss member 240 by means of a jogger plunger 241 adapted to be received by the hollowed interior of the boss member 240 which is rigidly secured to the vertical jogger back wall 237. A cam block 242 is positioned on the back face of the jogger plate 239 and is adapted to be contacted by a reciprocating cam bar 243 having an offset camming portion 244 formed therein. The inner end of the

camming bar 243 is connected to the cross connecting rod 162 extending between the rockable bell cranks 159 and 160, although connection might as conveniently be made with the stop finger bar 225 like in my first described jogger. It will be seen from this arrangement that to and fro movement of the camming bar, by movement of the cross connecting rod 162, causes an in and out movement of the jogger plate as the cam block is intermittently contacted by the camming bar. It might further be noted that a return impulsion of the jogger plate is provided for by means of a compressive spring 245 journaled in the boss member 240 surrounding the jogger plunger 241; movement of the jogger plate toward the stack of paper on tray 132 causing compression of the spring 245 which then exerts resilient returning pressure on the jogger plate through the intervening jogger plunger.

Use and operation

In use and operation my alternate feeder 131 is substantially identical to my previously described feeder 31; the sequence of operation and timing of the feed roll, stop fingers and jogger being generally the same as previously outlined in the operational description for feeder 31.

Figure 7 shows the feeder 131 at the start of the feeding cycle with the feed roll 133 down, in proximate contact with the retard roll 134, the stop fingers in a non-interfering position as shown in detail in Figure 8 and the jogger "out." Further counterclockwise rotation of the crank plate 204 and shaft 82 from their Figure 7 position, causes the straight connecting rod 203 to move to the right of its Figure 7 position pivoting the feeder bell crank 198 about its pivot point to raise the spool 195 on the hinge pin 152. The vertical movement of the spool upward on the hinge pin causes responsive rocking actuation of the clutch engagement lever 180 and with the clutch pin "in," the intermediate drive lever 173 will be rigidly tied to lever 180 to rock about shaft 176 in a clockwise direction causing counterclockwise actuation of the associated kick plate 168, connection therebetween being by the intermediate link 174.

As the kick plate moves counterclockwise the rack is pulled downwardly to rotate the feed roll 133 to feed a single sheet of paper to the feed rollers 27 of the press. It should be noted that during this feeding period the rocker arm 165 has remained in its Figure 7 position holding the feed roll in proximity with the retard roll by means of the cam roller 163 associated with the bell crank 159 which is held in engagement with the camming aperture 164 disposed near the upper end of the rocker arm. Similarly the stop fingers 135 are held in the down position shown in Figure 8 through the intervening linkages actuating the finger bar 225, comprising the connecting link 227, the curved intermediate lever 228, the vertical bell crank 229 and the roller 232, held in contact with the camming edge 233 of the rocker arm by spring 234.

As the kick plate continues to move counterclockwise, it eventually brings the right-hand hammer 169 into contact with the anvil block 170 on the rocker arm 165 to thereby force the rocker arm counterclockwise as well. Such movement of the rocker arm causes the cam follower 163 to assume its Figure 9 position at the opposite end of the camming aperture to raise the feed roll to its Figure 10 position away from the retard roll by clockwise rotational movement of the bell cranks 159 and 160. Likewise, the cam

roller 132 associated with the vertical bell crank 229 controlling the movement of the finger bar 225 and stop fingers 135, is moved upward along the upper camming edge 233 of the rocker arm 165 to raise the stop fingers to their Figure 10 position where they interfere with and prevent the movement of a sheet of paper from the stack into the feed rollers of the press; the single sheet previously fed to the stops of the press' feeding couple, however, lies over the top of the raised fingers. With the rocking motion of the left and right hand bell cranks 159 and 160, respectively, by the controlling movement of the camming aperture 164 along the cam follower 163, to raise the feed roll, the cross connecting rod 162 rigidly secured between the bell cranks activates the jogger linkage to put the jogger 136 "in," which causes the stack of paper in tray 132 to be pushed against the left-hand side plate 141 for proper alignment thereof, holding the sheets in their fanned or cascaded end relation in the stack, and at the same time aligns the "fed" sheet for proper gripping alignment in the feed rollers 27 of the press. The jogger remains in aligning contact with the single "fed" sheet during the feeding operation by the feed rollers 27 as well.

Naturally, with further counterclockwise rotation of the shaft 82 and attached crank plate 204, the connecting rod 203 will be pulled back from its Figure 9 position toward the start of the feeding stroke position shown in Figure 7. During this portion of the operating cycle the kick plate pushes the rocker arm to the right or clockwise, as seen in Figures 7 and 9, until it reaches its Figure 7 position with the associated feed roll down, the stop fingers down, the jogger "out" and the rack at the top of its stroke ready to rotate the feed roll for a repetition of the feeding operation to the stops associated with the feed rollers 27 of the press.

Thus, it is seen that I have illustrated a new and simple mechanical feeder attachment for use with a conventional offset type of printing press, that is perfectly synchronized with the printing cycle of the press and capable of ensuring a steady feeding of a single sheet of paper to the press thereby eliminating the cumbersome "hand feed" system presently employed in the industry.

While I have herein shown and illustrated two preferred forms in which my invention may appear, it will be readily understood that numerous changes, modifications, and substitution of equivalents and materials may be made without departing from the spirit and scope thereof, and, therefore, I do not wish to be restricted or otherwise limited to the specific embodiments herein illustrated, except as may appear in the following appended claims.

I claim:

1. In an automatic feeder mechanism for feeding paper sheets, a rotatable feed roll adapted to present a moving cylindrical surface to the upper surface of said sheets of paper, a stationary retard roll below said feed roll adapted to wipe the under surface of said sheets of paper and spaced from said feed roll a distance sufficient to allow the passage of a single sheet of paper at one time between said two rolls, cam means associated with said feed roll for intermittently raising said feed roll from approximate contact with the surface of said retard roll, linkage means associated with said camming means for actuation thereof, and stop fingers adapted to be raised to an interfering position with the path of movement of said sheets of paper across said retard roll for preventing

such passage during the period when said feed roll is withdrawn from approximate feeding contact with said retard roll.

2. A feeder mechanism for automatically feeding single sheets of paper from a stack of paper to a destination requiring intermittent but constant supply, comprising in combination, means for supporting said stack of paper during the selective feeding of the single sheet therefrom, rotative feed roll means for intermittently gripping the upper surface of a sheet of paper for intermittent feeding thereof, a stationary retard roll disposed below said feed roll adapted to be selectively positioned relative thereto so that a single sheet of paper will be separated from said stack and fed between said two rolls during said feeding by said feed roll, camming means for periodically moving said feed roll out of proximate feeding contact with said retard roll, means for periodically rotating said feed roll when said feed roll is in proximate relation with said retard roll, stop finger means for periodically stopping the passage of said paper between said two rolls, and jogger means for periodically contacting one side of said stack of paper to cause proper alignment thereof on said supporting means.

3. An automatic continuous feeder for supplying single sheets of paper to a destination requiring repetitive intermittent supply thereof, comprising, a periodically rotatable feed roll, a stationary retard roll stationed beneath said feed roll, clutch and pinion means associated with said feed roll for periodically rotating said feed roll, cam means for periodically raising and lowering said feed roll relative to said retard roll, said feed roll being capable of rotation when in its lowered proximate relation to said retard roll, a single driving link connected to a rotative crank plate, and inter-connecting linkage between said cam means and said driving link for actuating said cam; rack and pinion means associated with said feed roll and connected to said driving link for periodically rotating said feed roll, and stop fingers adapted to be raised and lowered to hold said paper from sliding between said two rolls when said feed roll is in its raised position and also adapted to allow said paper to pass between said rolls when said feed roll is in its lowered feeding position whereby said paper may be fed to said intermittently demanding destination in responsive sequence therewith.

4. An automatic feeder mechanism adapted to intermittently supply a press couple or the like in response to the intermittent demands thereof, comprising in combination, means for feeding a single sheet of paper to a suitable stop preparatory to passage thereof to said couple, means for aligning said paper in said feeding means for proper and accurate registration with said couple, means for releasing said feeding means from said sheet after said paper has met said stop, said paper being entirely free of external restraint except for aligning contact by said aligning means and said stop, whereby said sheet is accurately aligned for registered gripping thereof by said couple, and means for delaying said feeding actuation of said feeding means until said couple has received said sheet of paper and removed it from the feeder.

5. An automatic feeder mechanism adapted to intermittently supply a couple associated with a printing press or the like demanding an intermittent but repetitive supply of paper sheets, comprising in combination, rotatable feed roll means for periodically feeding paper sheets to

said press, stationary retard roll means disposed below said feed roll means and adjustable in its vertical position relative thereto whereby a passage is disposed between said two rolls adapted to receive but a single sheet of paper at one time for passage between said two rolls, linkage means associated with said feed roll for raising said roll on completion of said feeding operation thereof, said linkage also acting to lower said feed roll into feeding position and approximate contact with said retard roll, and selectively actuated rotative means for periodically rotating said feed roll when it has reached its feeding position in approximate contact with the surface of said retard roll.

6. An automatic feeder adapted for feeding sheets of paper to a printing press or the like comprising a cylindrical feed roll rigidly secured to a rotatable horizontal shaft, a sliding cam plate disposed transversely of said shaft and at one end thereof, said plate having an inclined camming aperture formed along its length adjacent said shaft end and adapted to receive said shaft end therethrough, and said sliding cam plate adapted to be actuated reciprocally along a horizontal path transversely of the axis of said shaft whereby said shaft will be raised and lowered in response to contact pressure exerted thereon by said camming aperture; a double T-shaped bell crank disposed parallel to and alongside but below said cam plate, adapted to reciprocate along an arcuate path about a horizontally disposed pivotal axis, a rod pivotally connected to an upper extending arm of said bell crank and slidably interconnecting said upper bell crank arm to said cam plate whereby upon rocking actuation of said upper arm toward said sliding cam plate, said plate will be slidably pushed in one direction and be slidably pulled in an opposite direction by said rod upon actuation of said upper bell crank arm in an opposite direction thereby causing said shaft to be raised and lowered in response to said sliding actuation of said sliding cam plate.

7. An automatic sheet feeder for selectively supplying sheets of paper to a printing press in response to the repetitive demands thereof, comprising, a crank motion producing connection between said feeder and a rotating shaft of said press, a double bell crank operatively engaging said cranking connection, said double bell crank being characterized by a central projecting stem and upper and lower arms disposed at right angles to said stem; a feed roll disposed centrally of a horizontally positioned shaft; a sliding cam plate operatively engaging one end of said latter shaft, said horizontal shaft being rotatably mounted between a pair of parallel spaced bell cranks pivotally tied to the framing of said feeder along coaxial pivot axes, and a lost motion connection between said upper arm of said double bell crank and said sliding cam plate, whereby said cam plate will periodically raise and lower said horizontal shaft and partially rotate said spaced bell cranks about said coaxial axes in response to rocking actuation of said double bell crank by said crank motion producing connection.

8. An automatic sheet feeder for selectively supplying sheets of paper to a printing press in response to the repetitive demands thereof, comprising a crank motion producing connection between said feeder and a rotating shaft of said press, a double bell crank operatively engaging said cranking connection, said double bell crank

being characterized by a central projecting stem and upper and lower arms disposed at right angles to said stem; a feed roll disposed centrally of said feeder on a horizontally positioned shaft, a sliding cam plate operatively engaging one end of said horizontal shaft, said horizontal shaft being rotatably mounted between a pair of parallel spaced bell cranks pivotally tied to the framing of said feeder along coaxial pivot axes; a rack adapted for vertical racking actuation connected to said stem of said double bell crank, and an override clutch and pinion disposed in operative engagement between said rack and said horizontal shaft supporting said feed roll whereby said shaft may be periodically rotated in one direction only during one stroke of said rack.

9. An automatic sheet feeder for selectively supplying sheets of paper to a printing press in response to the repetitive demands thereof, comprising a crank motion producing connection between said feeder and a rotating shaft of said press, a double bell crank operatively engaging said cranking connection, said double bell crank being characterized by a central projecting stem and upper and lower arms disposed at right angles to said stem; a feed roll disposed centrally of a horizontally positioned shaft, a sliding cam plate operatively engaging one end of said shaft, said shaft being rotatably mounted between a pair of parallel spaced bell cranks pivotally tied to the framing of said feeder along coaxial pivot axes, a rack adapted for vertical racking actuation connected to said stem of said double bell crank, an override clutch and pinion disposed in operative engagement between said rack and said horizontal shaft supporting said feed roll whereby said shaft may be periodically rotated in one direction only during one stroke of said rack, a stationary retard roll disposed below said feed roll, a plurality of stop fingers disposed in adjacent position to said retard roll and supported on a rotative shaft, a torsional spring disposed around said shaft, which supports said stop fingers, for normally urging said stop fingers to a non-interfering position out of the path of travel of said paper sheets between said two rolls; and a latch bar at one end of said stop finger shaft adapted to be rotated contra the torsional resistance of said spring by a cocking bar connected with said upper arm of said double bell crank whereby said stop fingers may be periodically raised to prevent the passage of said paper between said two mentioned rolls.

10. An automatic sheet feeder for selectively supplying sheets of paper to a printing press in response to the repetitive demand thereof, comprising a crank motion producing connection between said feeder and a rotating shaft of said press, a double bell crank operatively engaging said crank connection, said double bell crank being characterized by a central projecting stem and upper and lower arms disposed at right angles to said stem; a feed roll disposed centrally of a horizontally positioned shaft, a sliding cam plate operatively engaging one end of said horizontal shaft, said horizontal shaft being rotatably mounted between a pair of parallel spaced bell cranks pivotally tied to the framing of said feeder along coaxial pivot axes; a rack adapted for vertical racking actuation connected to said stem of said double bell crank; an override clutch and pinion disposed in operative engagement between said rack and said horizontal shaft, supporting said feed roll, whereby said shaft may be periodically rotated in one direction only during one

stroke of said rack, a stationary retard roll disposed below said feed roll, a plurality of stop fingers disposed in adjacent position to said retard roll and supported on a rotative shaft, a torsional spring disposed around said shaft which supports said stop fingers for normally urging said stop fingers to a non-interfering position out of the path of travel of said paper sheets between said two rolls, a latch bar at one end of said stop finger shaft adapted to be rotated contra the torsional urging of said spring by a cocking bar connected with said upper arm of said double bell crank whereby said stop fingers may be periodically raised to a position wherein said stop fingers interfere with the free passage of said paper sheets between said two rolls; a bell crank disposed below said latch bar, said bell crank having a lower arm fitted with a recessed detent at one end thereof adapted to engage and hold said latch bar in a position whereby said stop fingers are in said raised interfering position; and depending rod means associated with said cocking bar for periodically releasing said latch bar from engagement with said detent in response to lateral reciprocal movement of said cocking bar whereby said stop fingers may be lowered by said torsional spring to said non-interfering position.

11. In an automatic mechanical feeder for supplying sheets of paper to a printing press or the like, the combination comprising a rotatable feed roll, a rotatable transverse shaft for supporting said feed roll, a non-rotatable retard roll juxtaposed below said feed roll and adjustable in its horizontal relative position thereto, a pair of bell cranks associated with said shaft for raising and lowering said shaft and attached feed roll through an arcuate path, a cam roller on one of said bell cranks adapted to be engaged by a cam aperture formed in an arcuately actuated rocker arm, a reciprocal kick plate adjacent and parallel to said rocker arm adapted for arcuate pivotal movement about a shaft common to said kick plate and rocker arm, and anvil and hammer means disposed between said kick plate and rocker arm for intermittently reciprocating said rocker arm along an arcuate path in response to reciprocating movement of said kick plate.

12. In a feeder apparatus for intermittently supplying sheets of paper to a printing press couple or the like, a horizontally disposed rotatable shaft, a feed roll positioned intermediate the ends of said shaft, fixed thereto and adapted to rotate therewith; bell crank means associated with said shaft for the supporting thereof, said shaft being adaptable to be rocked along an arcuate path by said bell crank means, a rocker arm adapted to reciprocate along an arcuate path, cam means disposed between said bell crank means and said rocker arm for transmitting said rocking motion of said arm to said bell crank means whereby said shaft may be actuated along its arcuate path, kick plate means adapted for reciprocating movement about a pivotal shaft common with said rocker arm, an anvil on said rocker arm, a pair of hammer members disposed on either side of said anvil and rigidly secured to said kick plate, and selectively operable linkage means adapted to reciprocally oscillate said kick plate about said pivot shaft whereby said hammers will alternately strike opposite faces of said anvil to impart oscillating motion to said rocker arm.

13. In a feeder apparatus for intermittently supplying sheets of paper to a printing press couple or the like, a horizontally disposed ro-

5 tatable shaft, a feed roll positioned intermediate the ends of said shaft, fixed thereto and adapted to rotate therewith; bell crank means associated with said shaft for the supporting thereof, said shaft being adaptable for rocking movement along an arcuate path by said bell crank means, a rocker arm adapted to reciprocate along an arcuate path, cam means disposed between said bell crank means and said rocker arm for transmitting said rocking motion of said arm to said bell crank means whereby said shaft may be actuated along its arcuate path, kick plate means adapted for reciprocating movement about a pivot shaft common with said rocker arm, an anvil on said rocker arm, a pair of hammer members disposed on either side of said anvil and rigidly secured to said kick plate for alternately striking said anvil in response to arcuate actuation of said kick plate, an intermediate drive lever pivotally connected to said kick plate, a clutch engagement lever pivotally mounted adjacent said intermediate drive lever adapted to reciprocate about a common pivotal axis therewith, and a selectively engageable clutching means disposed between said two levers for selectively tying said levers rigidly together.

14. In a feeder apparatus for intermittently supplying sheets of paper to a printing press couple or the like, a horizontally disposed rotatable shaft, a feed roll positioned intermediate the ends of said shaft, fixed thereto and adapted to rotate therewith; bell crank means associated with said shaft for supporting said shaft, said shaft being adaptable to be rocked along an arcuate path by said bell crank means; a rocker arm adapted to reciprocate along an arcuate path, cam means disposed between said bell crank means and said rocker arm for transmitting said rocking motion of said arm to said bell crank means whereby said shaft may be actuated along its arcuate path, kick plate means adapted for reciprocating movement about a pivot shaft common to said rocker arm, an anvil on said rocker arm, a pair of hammer members disposed on either side of said anvil and rigidly secured to said kick plate, an intermediate drive lever pivotally connected to said kick plate, a clutch engagement lever pivotally mounted adjacent said intermediate drive lever adapted to reciprocate about a common pivotal axis therewith, a spool member slidably mounted on a vertical hinge pin for vertical sliding movement thereon, said spool being operatively connected with said clutch engagement lever; a feeder drive bell crank pivotally secured to said printing press for rocking driving movement, one end thereof connected to a crank motion producing source and the other end being connected to said spool whereby said linkage associated with said feed roll may be actuated.

15. An automatic feeder adapted to feed sheets of paper or the like to a printing press, comprising a pair of spaced vertically positioned end plates, a feed roll mounted to and rotatable with a shaft member disposed between said two end plates, bell crank means associated with said shaft for raising and lowering said feed roll along an arcuate path, reciprocating motion producing linkage means mounted on one of said end plates and associated with said shaft and bell crank means to impart said raising and lowering motion to said feed roll, rack means operatively engaging a pinion on said shaft for rotating said shaft and feed roll, clutch means associated with said pinion for periodically stopping rotating move-

ment thereof produced by said rack, hinge means interposed between said feeder and said press whereby said feeder may be swung pivotally about said hinge means, reciprocating drive motion producing means driven by said press and adapted to impart vertical oscillatory sliding movement to a spool member associated with said hinge means, and connective means between said vertically oscillating spool and said linkage means for transmitting said reciprocating drive motion to said feeder.

16. An automatic feeder adapted to feed sheets of paper or the like to a printing press, comprising a pair of spaced vertically positioned end plates, a feed roll mounted to and rotatable with a shaft member disposed between said two end plates, bell crank means associated with said shaft for raising and lowering said feed roll along an arcuate path, reciprocating motion producing linkage means mounted on one of said end plates and associated with said shaft and bell crank means for actuating said bell crank to impart said raising and lowering motion to said feed roll, rack means operatively engaging a pinion on said shaft for rotating said shaft and feed roll, clutch means associated with said pinion for periodically stopping rotating movement thereof produced by said rack, hinge means interposed between said feeder and said press whereby said feeder may be swung pivotally about said hinge means, reciprocating drive motion producing means driven by said press and adapted to impart vertical oscillatory sliding movement to a spool member associated with said hinge means, and clutch means associated with said linkage means whereby said reciprocating motion imparted thereto through said oscillating spool may be utilized at will to drive said feeder.

17. An automatic feeder adapted to feed sheets of paper or the like to a printing press, comprising a pair of spaced vertically positioned end plates, a feed roll mounted to and rotatable with a shaft member disposed between said two end plates, a pair of bell cranks associated with said shaft for raising and lowering said feed roll along an arcuate path, reciprocating motion producing linkage means mounted on one of said end plates and associated with said shaft and bell cranks for actuating said bell cranks to impart said raising and lowering motion to said feed roll, rack means operatively engaging a pinion on said shaft for rotating said shaft and feed roll, clutch means associated with said pinion for periodically stopping rotating movement thereof produced by said rack, hinge means interposed between said feeder and said press whereby said feeder may be swung pivotally about said hinge means, reciprocating drive motion producing means driven by said press and adapted to impart vertical oscillatory sliding movement to a spool member associated with said hinge means, and means operable by said linkage means for periodically actuating stop fingers disposed below said feed roll whereby said paper sheets will be prevented from entering the press when said feed roll is in its non-rotating condition.

18. A mechanical sheet feeding device adapted to feed single sheets of paper to a printing press or the like, comprising a pair of vertically disposed parallel spaced end plates rigidly tied to one another, a rotatable feed roll disposed intermediate said end plates on a rotatable shaft, bell crank means pivotally connecting said shaft to said end plates, reciprocating mechanical

linkage means disposed on one of said end plates for intermittently raising and lowering said feed roll, rack means vertically reciprocated by said linkage means for rotating said feed roll when in its lowered position only, a paper holding tray disposed between said end plates for supporting paper sheets at an incline thereon, a non-rotatable retard roll juxtaposed below said feed roll and adapted to act as a frictional deterrent to free passage of paper between said two rolls, said rolls always being spaced apart; adjustable means associated with said retard roll for varying the spacing between said two rolls, said feed roll being movable along an arcuate path with a constant throw and being adapted to feed sheets of paper across said retard roll from said tray to said printing press, the adjusted vertical position of said retard roll determining the thickness of paper adapted to pass between said two rolls; and jogger means disposed on said tray and impelled by said reciprocating mechanical linkage for intermittently contacting one lateral edge of said paper sheets on said tray to thereby cause proper alignment thereof in said press when said feed roll is raised to its non-rotative, non-feeding position preparatory to a couple of said press receiving said paper sheets.

19. In an automatic feeder adapted to be mounted to a printing press or the like for supplying paper sheets to said press in response to the demands thereof, the combination comprising an inclined tray means for supporting said paper whereby said paper may be gravitationally fed along said tray, feed roll means disposed above said tray at the lower end thereof, means for intermittently raising and lowering said feed roll, means for intermittently rotating said feed roll, rotation occurring when said roll is in its lowered position; jogger means disposed along one side of said tray for periodically contacting said paper sheets thereon whereby said paper may be properly aligned for feeding contact by said feed roll, said jogger acting in response and in integrated sequence with said raising and lowering of said feed roll; and stop finger means disposed below and on either side of said feed roll adapted to be raised to an interfering position with the path of movement of said paper therebeneath when said feed roll is raised, said stop fingers also adapted to be lowered to a non-interfering position with said path of movement of said paper when said feed roll is lowered, by which arrangement said paper is prevented from passing into said printing press unless fed thereto by said feed roll.

20. In an automatic feeder for supplying sheets of paper to a couple of a printing press or the like, a feeder supporting frame comprising a pair of spaced parallel vertically disposed end plates, rotatable feed roll means disposed between said end plates, non-rotatable retard roll means juxtaposed below said feed roll, said two rolls being spaced apart to allow paper sheets to be fed therebetween; a vertical rocker arm pivotally connected to one of said end plates, a kick plate pivotally mounted adjacent and on a common axis with said rocker arm for actuating said arm with a reciprocating arcuate movement about said pivotal axis, a broken linkage disposed between said kick plate and a driving spool mounted for vertical sliding movement on a hinge pin secured to said printing press, pin clutch means associated with said broken linkage for selectively solidifying said linkage to cause driving motion transfer to said rocker arm

and kick plate therethrough, bell-crank and shaft means associated with said feed roll for raising and lowering thereof in response to movement of a cam surface, formed in said rocker arm, in a direction normal to the longitudinal axis of said feed roll shaft, rack means actuated by said kick plate for periodically rotating said feed roll, selectively positioned stop fingers disposed below said feed roll adapted to be raised and lowered by a suitable stop finger linkage responsive to an additional camming surface disposed along the upper edge of said rocker arm, and driving link means connected to said driving spool and responsive to the cyclic operation of said press for imparting reciprocating motion to said rocker and said cam plate.

21. A feeder as set forth in claim 20 wherein said spool is rotatable about said hinge pin to thereby provide means whereby said feeder may be swung laterally about said pin without disconnecting said driving link means from said spool, and whereby said feeder may be divorced from its normal position wherein said paper being fed by said feed roll will register with feed rolls of said press, thus providing ready inspection accessibility to said various feeder linkages without disturbing the cyclic operation of said feeder.

22. In an automatic continuous feeder for supplying paper sheets to the feeding couple of a printing press or the like, feed roll means for periodically feeding said sheets up against stops associated with said feeding couple of said press, stop finger means associated with said feed roll means for intermittently preventing the passage of said sheets to said stops when said feed roll is not feeding, and jogger means associated with said stop fingers for aligning said sheets for proper registration and reception by said feed roll, feeding couple and press comprising a cam linkage responsive to said periodic actuation of said feed roll and a face plate connected to said cam linkage, said face plate being adapted to contact said paper along one edge thereof when said stop fingers are placed in an interfering position relative to said paper sheets, to remain in aligning contact therewith during said feeding by said feeding couple and until another of said sheets is brought into feeding engagement with said feed roll and to be disengaged from said paper sheets upon the lowering of said stop fingers to allow the feeding of said paper sheets to said feeding couple.

23. In an automatic mechanical feeder apparatus for supplying sheets of paper to a feeding couple of a printing press or the like, feed roll

means adapted to periodically feed paper sheets to stops associated with said press feeding couple, stop finger means adapted to be raised and lowered in sequential relation to said periodic feeding operation of said feed roll, said fingers being raised to prevent the passage of additional sheets to said feeding by said feed roll, and jogger means adapted to periodically engage one lateral edge of a sheet of said paper upon raising of said fingers to thereby cause proper registering alignment and gripping of said sheet prior to engagement thereof by said feed roll and additionally adapted to remain in contact therewith during said feeding to said press by said feeding couple; disengagement of said jogger from said sheet occurring upon the lowering of said stop finger means.

24. In a sheet feeder for supplying sheets of paper or the like to the feeding couple of a printing press or the like, an inclined tray positioned opposite said feeding couple exteriorly of said press, a feed roll rotatably mounted above the inner end of said tray, a stationary retard roll mounted below said feed roll, said feed roll being adapted to be lowered toward said retard roll and rotated in this position to feed sheets from a stack of paper supported on said tray, stop fingers adapted to be raised to prevent said stack from sliding into said feeding couple when said feed roll is raised, the sheet previously fed to said couple lying over said fingers prior to removal thereof by said couple; and jogger means along one side of said tray for contacting the adjacent edge of said paper stack when said fingers and feed roll are raised to thereby maintain said stack in its proper feeding condition, wherein the end thereof adjacent said retard rolls is in an upwardly sloping cascaded condition and at the same time serving to align said sheet overlying said fingers for proper reception and alignment by said press feeding couple.
